DESIGN FOR A DOLL'S HEAD

Robert C. Finkelstein, New York, N. Y.

Application January 4, 1946, Serial No. 125,273

Term of patent 7 years

(Cl. D34—4)

To all whom it may concern:

Be it known that I, Robert C. Finkelstein, a citizen of the United States, residing at New York, in the county of New York, city and State of New York, have invented a new, original, and ornamental Design for a Doll's Head, of which the following is a specification, reference being had to the accompanying drawing, forming part thereof.

In the drawing

Fig. 1 is a front elevational view of a doll's head, showing my new design;

Fig. 2 is a side elevational view thereof; and
Fig. 3 is a top plan view.

I claim:

The ornamental design for a doll's head, substantially as shown.

ROBERT C. FINKELSTEIN.
